[57] CLAIM

The ornamental design for a wheel cover, as shown and described.

DESCRIPTION

FIG. 1 is a front elevational view of the wheel cover showing my novel design;

FIG. 2 is a sectional view taken along the plane indicated by line 3—3 in FIG. 1;

FIG. 3 is a sectional view taken along the plane indicated by line 4—4 in FIG. 1; and

FIG. 4 is a perspective view of a wheel cover showing a second embodiment of my new design it being understood that the sole difference resides in the center disc being plain and unornamented.
